DESIGN FOR A FEEDING CUP OR SIMILAR ARTICLE

Charles C. Cooner, Jr., New Kensington, Pa., assignor to The Aluminum Cooking Utensil Company, New Kensington, Pa., a corporation of Pennsylvania

Application December 15, 1939, Serial No. 88,914

Term of patent 7 years

To all whom it may concern:

Be it known that I, Charles C. Cooner, Jr., a citizen of the United States, residing at New Kensington, in the county of Westmoreland and State of Pennsylvania, have invented a new, original, and ornamental Design for a Feeding Cup or Similar Article, of which the following is a specification, reference being had to the accompanying drawing, forming a part thereof, in which:

Fig. 1 is a top plan view of the article showing my new design;

Fig. 2 is an elevational view; and

Fig. 3 is an elevational view taken from the right in Fig. 2.

I claim:

The ornamental design for a feeding cup or similar article, substantially as shown.

CHARLES C. COONER, JR.
